PORTABLE BENCH FOR PACKING HOUSES

Bessie Linn Smith, Avon Park, Fla.

Application May 5, 1933, Serial No. 669,616

Renewed August 17, 1935

6 Claims. (Cl. 226—129)

The invention concerns apparatus for use in packing houses, for instance, where citrus fruit is packed in boxes for shipment. The invention resides in the features and combination and arrangement of parts hereinafter described and particularly pointed out in the claims.

In the drawings

Figure 1 is a diagram of the apparatus in plan view.

Fig. 2 is a side elevation of a portable carrier or bench for the box of fruit or other article.

Fig. 3 is a detail view of a supporting member for the box to be packed.

Fig. 4 is a further detail view.

Fig. 5 is a plan view of a conveyor and a box stop. This view also illustrates the portable bench or packing box carrier in its relation to the conveyor for delivering the packed boxes thereon.

Fig. 6 is a side view of a portable bench or box carrier in modified form.

Fig. 7 is a detail view of parts of Fig. 6.

Fig. 8 is a plan view of a portable bench in modified form.

Fig. 9 is a side view of the bench of Fig. 8.

Figs. 10 and 11 are views of a box stop to be associated with the conveyor.

Referring to Fig. 1 *a* indicates in plan view a series of bins from which the fruit or other articles are taken by the attendant and packed in a box mounted on a portable bench or carrier. A number of these carriers are indicated at *b* in proper relation to the bins to enable the attendants to do the packing. In this diagram also is indicated a conveyor *c*, composed of parallel stretches or lines of links for supporting the box of fruit when delivered thereupon by moving a bench from the position adjacent the bins to the position indicated at *x*. At this station there is provided a box stop *d* adapted to arrest the box in proper relation to the conveyor when said box is moved from the portable bench onto the conveyor.

The portable bench as shown in Fig. 2 consists of a body portion *b'* of any suitable construction mounted upon casters *e* and provided at its upper end with supporting means for the packed box, which supporting means presents an inclined trackway down which the box may move so as to be discharged onto the conveyor.

The inclined way in Fig. 2 is made up of a series of rollers *f* mounted in a bar or frame *f'*, secured to the top of the body of the bench in any suitable manner. These rollers may be of the same diameter, but they are arranged with their axes in an inclined plane. The frame members or bars

f' in which these rollers are journaled extend beyond the front of the bench as indicated at *y* so as to overlie the conveyor *c* when the bench is moved into the position indicated at *x* in Fig. 1. During the packing operation the box is supported on the inclined surface afforded by the several rollers *f* at a point directly above the body of the bench. With the box in this position the bench is moved from the bin to a point opposite the box stop *d* in Fig. 1, so that the over-reaching or over-hanging forward portions of the track bars *y* will overlie the conveyor belt. The box with its packed fruit is then moved down along the incline towards the belt, and having reached the desired position, the bench is withdrawn so that the box is deposited in the proper position onto the conveyor. The box stop determines in large degree the proper position of the box, which in being delivered upon the conveyor contacts with this stop, and is thus limited as to its further movement transversely of the conveyor.

Instead of having the track bars *f'* with inclined upper edges, they may be of the form shown in Fig. 3, in which instance the anti-friction rollers are of different diameters so that the inclined track or surface along which the packed box moves, will be provided. Instead of the rollers the track members or inclines may be of the form shown in Fig. 4, presenting plain upper inclined edges down which the box may be moved by the operator. A handle is provided at *g* by which the bench may be moved from place to place.

The box stop *d* may consist of a bar or strip of comparatively thin material, presenting its edge for contact with the box so that small frictional resistance will be afforded by reason of this contact.

As shown in Figs. 10 and 11, there may be two of these box stop bars *d*, one above the other. A suitable support such as *d'* may be attached to the floor to hold these box stop strips in proper spaced apart relation to each other.

In Figs. 6 and 7 there is shown a modified form of the inclined tracks or surfaces, down which the packed box may be moved, this modification comprising a collapsible feature, whereby when the bench is being moved about the packing house in an empty condition, the overhanging front ends of the track members or box delivering support may be moved to a position where it is out of the way. This may be accomplished in various ways, but in the particular form shown in Figs. 6 and 7 the structure includes a pivotal mounting of the forward ends *f''* of the support or

track bars, consisting of pivot members f^3 passing through slots f^4 in the track bar sections f^2 . These track bar sections also have notches such as shown at f^5 to engage pins f^6 projecting from 5 the main fixed portions f^1 of the track bars.

These hinged forward sections f^2 , by the construction just described, may be collapsed into the position shown in Fig. 7, where they hang down at the front of the bench. They may be 10 so collapsed when the box is being filled, or when the carrier is being moved from place to place. When, however, the carrier is in use, in the act of transporting a filled box from the bin to the conveyor, the collapsible extensions should be in 15 the position shown in Fig. 6 so that they can be made to overlie the conveyor for the delivery thereupon of the packed box.

Instead of having these track sections collapsed in the form above described, they may 20 be hinged as shown in Figs. 8 and 9 to swing laterally from the extended positions shown at f^7 to the dotted line positions shown at f^8 .

The pivotal mountings for these track members are indicated at h .

25 Any suitable means may be used for holding the packed box against movement along the top of the portable bench during transportation, such for instance, as the hooks k , Fig. 5 suitably pivoted to the top of the portable bench, for engaging the box. These holding means may be desirable where the inclined track surface is made up of rollers, but where the rollers are omitted, such for instance, as in Figs. 8 and 9, there would 30 be sufficient frictional resistance to the movement of the box down the incline as would render unnecessary the use of these catches or holding hooks. It will be understood, however, that whether the anti-friction rollers are used or not, the incline at the top of the portable bench i. e. 35 along the track members, will be sufficiently steep to materially aid in the movement of the box into a position to be delivered onto the conveyor.

At d^2 Figs. 10 and 11 are shown brackets to 40 reach under the conveyor to steady the box stop standards when unusual pressure is imposed on the box stop by the box under careless handling.

The box stop d is provided with bevelled or 45 rounded ends to prevent the box from being arrested in its movement with and along the conveyor. The movement of the conveyor chains must not be interfered with, which might happen if the operator should carelessly deposit the box slightly to one side of the box stop where its side might hit against the end of the box 50 stop hard.

The track way may assume different forms. I 55 prefer to provide this track way in the form of spaced apart bars or tracks whether provided with anti-friction rollers or not, though I do not limit myself to the spaced apart feature. This, however, reduces the friction surface. Furthermore, the spacing of the bars or tracks provides a free space between them in which a 60 packer can stand so as to be close to the body of the bench, if it is desired to not utilize the collapsible feature of the projecting bars or tracks.

I claim:

1. In combination, a portable packing bench 70 having a trackway at its top inclined downwardly toward its discharge end and providing a platform for holding a container to be packed, the discharge portion of said trackway projecting beyond the body of said bench to overlie a free space therebeneath, and means carried by the

5 bench for holding the container to be packed on the portion of the inclined trackway above the body of the bench, said holding means being detachable from the container to permit its movement down the trackway to the projecting portion.

2. In a portable packing bench a body structure and a trackway carried thereby for supporting a container, said trackway having a portion extending along the top of the body structure 10 and having a portion supported entirely by the bench in laterally projecting relation thereto beyond the top thereof to overlie a free space therebeneath and permit the bench to be moved adjacent a conveyor with the projecting portion 15 of the trackway overlying the same, the trackway portion above the body structure providing a platform on which a container may be placed during packing and along which the container may be shifted toward the side of the bench at which the 20 packer stands in packing and from which the projecting portion extends, said projecting portion slanting downwardly away from the bench to gravitationally deliver a container onto a conveyor within said free space and said projecting 25 portion comprising two parallel spaced apart arms providing a space between them to receive a packer close to the body structure, said trackway being unidirectional throughout its extent whereby a container moving therealong and down 30 the inclined portion will be deposited upon a conveyor upon withdrawal of the bench in a direction parallel with the length of the trackway and counter to the movement of the container, said trackway extending in a direction to deliver the 35 container toward the side at which the packer stands.

3. A portable packing bench according to claim 2 in which the portion of the trackway above the body structure is inclined downwardly toward the 40 projecting portion to tilt a container thereon about an axis longitudinal of the container and toward a packer standing at that side.

4. A portable packing bench comprising a supporting body structure which is of oblong shape 45 in horizontal dimensions, wheeled means at the bottom of the bench for enabling movement of the bench from a packing bin to a conveyor, and tracks on the top of the bench disposed at the narrow ends of the bench, said tracks extending 50 parallel with the narrower dimension of the bench and transversely to a long side thereof, said tracks providing rests upon which a container may be placed during packing to present a longer side of the container toward the long side of the 55 bench with respect to which the tracks are transverse, the transverse positioning of the tracks relative to said long side serving to deliver the container toward that side so that the container will be delivered from the bench with its longer 60 dimension in parallelism with the longer dimension of the bench.

5. A bench according to claim 4, in which the tracks slope downwardly toward said long side with respect to which the tracks are transverse. 65

6. A portable packing bench comprising a supporting body structure against one side of which a packer is intended to stand, and a trackway carried thereby for supporting and delivering a container, said trackway having a portion above 70 the bench and a portion projecting from the bench and beyond the side of the bench at which a packer stands, said projecting portion being wholly supported by the bench so that a free space is therebeneath to receive a conveyor, said 75

trackway being unidirectional throughout its extent and being positioned transverse to the side of the bench at which a packer stands, the trackway portion above the body structure providing a 5 platform on which a container may be placed during packing with a long side of the container toward the packer to facilitate access to the interior thereof, the positioning of said trackway transverse to the side at which the packer stands 10 and the projection of the projecting portion from

that side serving to move a container toward the packer's side of the bench and to deliver a container from the bench in parallelism with its positioning on the bench, said projecting portion of the trackway being collapsible relative to the 5 bench in substantially the same horizontal plane in which it lies when projecting, said projecting portion when collapsed facilitating movement of the packer.

BESSIE LINN SMITH. 10
